(57) **CLAIM**

The ornamental design for a hose connector as shown and described.

DESCRIPTION

FIG. 1 is a front view of a hose connector;
FIG. 2 is a rear view thereof;
FIG. 3 is a top view thereof;
FIG. 4 is a bottom view thereof;
FIG. 5 is a right side view thereof;
FIG. 6 is a left side view thereof;
FIG. 7 is a first perspective view of the front, top, and right side thereof; and,
FIG. 8 is a second perspective view of the rear, top, and left side thereof.

The broken lines shown in the figures of the drawing illustrate portions of the hose connector and form no part of the claimed design.

The alternate long dash and short dash lines shown in the figures of the drawing illustrate the boundary between the claimed portions of the design and the portions of the design shown in broken lines.
